SHOCK ABSORBING INSOLE AND ARCH CUSHION

William M. Scholl, Chicago, Ill.

Application August 21, 1957, Serial No. 679,330

4 Claims. (Cl. 36—71)

This invention relates to improvements in a shock absorbing insole and arch cushion, and more particularly to such a device for disposition in an article of footwear beneath the plantar surface of the human foot, the invention being particularly designed to give support, protection, and cushioning effect to the weight carrying portions of the foot, namely the tarsus and metatarsus, although the invention may have other uses and purposes as will be apparent to one skilled in the art.

In the past, many and various types of cushion supports for the foot have been developed, but in most instances these devices were not as easy to fit into a shoe and retain their position as is desired, were not designed to properly cushion as well as support the various parts of the foot, and did not properly provide relief for foot strain, fatigue and exhaustion by cushioning properly and substantially the entire plantar surface of the foot.

With the foregoing in mind, it is an important object of the instant invention to provide both a shock absorbing and cushion supporting device shaped to give support and cushioning effect, not only to the bearing points of a normal foot, but also to the parts of a foot between and around those bearing points.

Another object of the instant invention is the provision of a soft, very light, and airy or ventilated foot cushion which may readily be slipped into an article of footwear and effectively retain its original position against any tendency to shift.

Also an object of the instant invention is the provision of a shock absorbing cushioning insole capable of providing added cushioning effect during walking by virtue of the porous quality of the insole and the pumping of air at each step.

A further feature of the instant invention resides in the provision of a shock absorbing insole embodying added individual supporting elements at separate locations, the construction being such that there is no objectionable or irritating wrinkling or buckling of the insole during use.

Another feature of the instant invention resides in the provision of a shock absorbing insole embodying a number of initially separate pieces, all supporting pieces being secured to the cover member only of the insole, and a separate cushioning under layer being secured to the cover only around the bounding margin or edge of the device, but otherwise unsecured to the cover or any of the separate supporting elements.

Still a further feature of the instant invention resides in the provision of a shock absorbing insole carrying separate supporting elements therein which includes a cover layer, and an underlying cushioning bottom layer or sheet in addition to the separate supporting elements, with the supporting elements heat sealed to one of the layers and not to the other, certain of the heat seal seams providing a bending or hinge function whereby a portion of the device may be disposed at an angle to the rest without buckling or wrinkling in any of the structure.

It is also an object of this invention to provide a

2

shock absorbing insole embodying initially separate and spaced individual supporting elements secured to an overlying cover sheet with an extension on that cover sheet in the region of the metatarsal arch to bend upwardly against the upper of a shoe.

While some of the most salient features, characteristics and advantages of the instant invention have been above pointed out, others will become apparent in the following disclosures, taken in conjunction with the accompanying drawing, in which:

Figure 1 is a top plan view of a shock absorbing insole and arch cushion embodying features of the instant invention;

Figure 2 is a bottom plan view of the structure of Figure 1;

Figure 3 is an enlarged transverse vertical sectional view taken substantially as indicated by the line III—III of Figure 1 looking in the direction of the arrows; and

Figure 4 is an enlarged transverse vertical sectional view taken substantially as indicated by the line IV—IV of Figure 1.

As shown on the drawings:

While the illustrated embodiment of the instant invention is shown in the form of a shock absorbing insole and arch cushion device which extends from the rear of the heel of the user, to a point just beyond the metatarsal arch with parts of the toes extending forwardly beyond the device to provide ample toe room within a shoe or the like, it is to be understood that certain features of the invention may well be incorporated in supporting and cushioning devices for disposition beneath the plantar surface of the human foot of various other shapes in the event it is not desired to correct or support as many parts of the foot as the instant device is capable of supporting. However, the illustrated embodiment of the invention is designed not only to give support and cushioning effect to the weight carrying portions of the foot, namely the tarsus and metatarsus, and thereby better balance the foot, but the invention also lends cushioning aid not only to the individual bearing points of the foot but the parts of the foot intermediate those bearing points.

With reference now to the drawings, it will be seen that the illustrated embodiment includes a cover sheet 1 preferably provided with numerous perforations throughout as indicated at 2. At one side of the cover sheet 1, and preferably opposite the longitudinal arch of the foot the cover is provided with an integral extension 3. A bottom sheet 4 of cushioning material underlies the entire cover 1 with the exception of the extension 3. This bottom cushioning sheet is preferably of a foam material having intercommunicating cells so as to provide adequate ventilation and provide an added cushioning effect due to the pumping action caused by the application and release of pressure upon the device during walking. Such intercommunicating cellular cushioning sheet coupled with the perforations in the cover 1 provide an added cushioning and shock absorbing effect to the device during walking by virtue of the air being forced in and out of the cushion at each step.

Preferably the cover sheet 1 and the cushioning sheet 4 are made of thermoplastic material of the character that may readily be heat sealed. Various thermoplastics are suitable for this purpose. By way of example, however, and not by way of limitation, I may mention that a satisfactory substance for the thermoplastic foam bottom sheet 4 is a vinyl foam made from a liquid composition generically known as a plastisol. This plastisol may be expanded by the use of an inert gas or otherwise, and then cured in the expanded condition to provide a light weight structural material which is highly flexible, highly resilient, possesses great restorative prop-

erties, and is provided with intercommunicating cells. This plastisol may satisfactorily be a dispersion or suspension of polyvinyl chloride resin, or a copolymer in one or more plastisizers selected from a large number of high boiling esters, for example, such as diethyl phthalate, diethyl adipate, dicapryl phthalate, etc. The top cover sheet 1 is preferably a film and may be made of the same material as the foam cushioning sheet, but if so, the resins and plastisizers are charged into a Banbury mill and from there passed to a calender which rolls out the finished product, thereby making the top sheet more in the nature of an unsupported vinyl film. Obviously, the top sheet is far denser than the foam cushioning sheet.

A segment shaped piece 5 of thermoplastic foam is preferably provided beneath the longitudinal arch of the foot, and as seen in Figures 1 and 3, this segment shaped piece of foam is preferably heat sealed, such as by high frequency electronic heat sealing, to the cover 1 only, along a curvate heat seal seam 6, and substantially longitudinally heat seal seam 7. In each instance, where a foam member is heat sealed to a film member, the heat seal is preferably of such character that the foam layer will be provided with curvate edges as indicated at 8 in Figure 3, whereby there are no abrupt elevations in the finished device.

A generally ovate metatarsal lift, which may satisfactorily be a piece of thermoplastic foam 9, is also secured only to the cover 1 by means of a heat seal seam 10 around the bounding edge of the lift 9. Preferably this metatarsal lift is of such size that the first and fifth metatarsal heads will fall on opposite sides of the lift, but rest upon the cover member above the underlying cushion sheet 4.

Beneath the extension 3, there is a small bottom piece 11 which may satisfactorily be of the same film as the cover. This piece is heat sealed to the cover along its outer edge by a heat seal seam 12. Between the cover extension 3 and the under piece 11 is another cushion element 13 which may satisfactorily be of the same thermoplastic foam above described, and this piece of material is caught in the aforesaid heat sealed seam 12 at its outer bounding edge, but the inner bounding edge thereof is heat sealed to the small underlying piece 11 only by a heat seal seam 14 which also connects the 45 underlying piece 11 with the bottom cushion sheet 4 along the inner side of the extension.

The bottom cushion sheet 4 is secured to the cover only except for the seam 14 as above explained, around the bounding edge of the device, and this also is preferably a heat seal seam 15, but the bottom cushion layer is otherwise free from securing to the cover 1 and to any of the added cushion lifts. As seen best in Figure 3, the seam 4 along the inside of the extension is a composite seam connecting the under piece 11 with the lift 13 and also connecting the under piece 11 with the cushion bottom sheet 4, but preferably the lift 13 and the sheet 4 are not directly connected to each other at this point.

Looking again at Figure 3, it will be noted that the heat seal seams 7 and 14 conjointly provide a hinge effect, whereby the extension including both the cover part 3, the under piece 11 and the lift 13 may readily be bent upwardly along the inside of the shoe upper, these two heat seal seams conjointly forming hinge means for that purpose.

It should also be especially noted that by virtue of the bottom cushion sheet 4 being free from the other portions of device except for the heat seal seams 14 and 15, relative movement between the cover and the lifts and the bottom layer is provided, so that during use there is no objectionable or irritating wrinkling or buckling of the device at any place. Also, during use, the intercommunicating cells in the bottom sheet 4, as

well as the intercommunicating cells in the various lifts 5, 9 and 13 cause air to be pumped through the device and the perforations in the cover pass some of that pumped air so that the foot is not only adequately ventilated, but there is an added cushioning effect by virtue of that air pumping.

Further, it will be readily understood that the device not only affords an adequate cushioning beneath the three bearing points of the foot, namely the os calcis, 10 and the first and fifth metatarsal heads, by virtue of the bottom sheet 4, but it also lends a cushioning lift to the metatarsal arch and the side of the foot adjacent that arch by virtue of the added cushion lift 5 and the lift 13, and further adequately supports the metatarsal arch by virtue of the added cushion lift 9, whereby the device supports all parts of the foot intermediate the normal three bearing points, stabilizes the foot, and will obviously greatly relieve foot strain, fatigue, and exhaustion. In addition, it may be mentioned that the device is extremely light in weight, may be made in any desired colors, and laundered whenever deemed necessary.

It will be understood that modifications and variations may be effected without departing from the scope of the 25 novel concepts of the present invention.

I claim as my invention:

1. A shock absorbing foot and arch cushion, comprising a thermoplastic cover sheet, a thicker thermoplastic foam sheet underlying said cover sheet, an added piece 30 of thermoplastic foam positioned to underlie the longitudinal arch of the foot, and an added piece of thermoplastic foam positioned to support the metatarsal arch of the foot, said added pieces being secured to said cover sheet, and said foam sheet being secured to said cover sheet at the bounding edges, a lateral extension on said cover opposite the longitudinal arch supporting foam piece, a small thermoplastic bottom piece under said extension, and a foam piece in said extension joined to said extension and said bottom piece, and the inner edge 35 of said bottom piece being joined to said foam sheet by a seam functioning also as a hinge to permit said extension to readily bend up inside a shoe against the upper of the shoe.
2. In an arch cushioning insole for a shoe, a cover sheet in the form of a thermoplastic film having a lateral extension in the region of the longitudinal arch, a small piece of thermoplastic film underlying said extension, a thermoplastic foam arch cushion secured to said cover sheet inside said extension, a thermoplastic foam pad 40 between the films of the extension and secured thereto along the outer boundary of the extension, and a thermoplastic foam sheet underlying said cover sheet except for said extension and secured to said cover sheet at the bounding edge of the device and similarly to said small piece of film along the inside of said extension.
3. In a cushion insole, a cover sheet, a cushion element secured to the underside of said cover, and a bottom cushion sheet secured at the bounding edge of the device to said cover and otherwise free of securing to said 45 cover and said cushion element, and said cover having a lateral extension in the region of the longitudinal arch, an extra sheet beneath said extension and secured at its outer margin to said cover, a cushion element between said extension and said extra sheet, and the inner edge 55 of said extra sheet being secured to both the last said cushion element and said bottom cushion sheet.
4. In a cushion insole, a cover sheet having a lateral extension to turn upwardly against a shoe upper in the region of the longitudinal arch of the foot when the 50 insole is placed in a shoe, an arch supporting cushion underlying said cover sheet and secured to said sheet by a hinge seam defining the inner side of said extension, a small sheet underlying said extension and secured to said cover sheet at the outer edge of said extension, a layer of cushioning material between the cover extension 55 and the arch supporting cushion.

and said small sheet and secured to said small sheet in a hinge seam substantially in vertical alignment with the first said hinge seam, and a bottom layer of cushioning material underlying said cover and said arch supporting cushion inside said extension and secured to said cover 5 along the bounding edge of the insole and to said small sheet along the inside of said extension.
